UNITED STATES PATENT OFFICE.

FRED WALDORF, OF PITTSBURGH, PENNSYLVANIA.

CONTROLLER FOR AUTOMOBILE LAMPS.

Application filed May 4, 1923. Serial No. 636,686.

To all whom it may concern:

Be it known that I, FRED WALDORF, a citizen of the United States, residing at Pittsburgh, in the county of Allegheny and 5 State of Pennsylvania, have invented new and useful Improvements in Controllers for Automobile Lamps, of which the following is a specification.

My invention relates to controllers for 10 automobile or other lights.

The laws of the several States require that the lamps of automobiles parked in public places shall be lit at a certain hour in the evening. It is the object of my invention to provide a time-controlled device 15 which may be set to cause the lamps to be lit at any desired time and to remain lit, if desired, for a definite period, as, for example, until a definite time before sunrise. 20 I obtain these results without disturbing the usual manual control of the lamps. Other objects appear hereinafter.

Referring to the accompanying drawings, 25 Fig. 1 is a diagrammatic view showing the electric system and portions of the clock mechanism for controlling the electric system; Fig. 2 is a side view of a portion of the mechanism, the gearing being arranged in a line for the sake of clearness; and Fig. 30 3 is a fragmentary view showing a portion of the trip-setting devices; and Fig. 4 is a diagram of the circuits of a modification of my invention. Fig. 5 is an elevation of the lever 61 and adjacent parts, and Fig. 6 is 35 a plan view of the lever 66.

On the drawings, 1 designates the bright head-lamps, 2 the dim lamps, 3 the dash lamp, and 4 the tail lamp.

5 is a switch pivoted between its ends on 40 the pivot 6 and having the arm 7 constructed to engage either the contact 8 or the contact 9. It has the wide arm 10 arranged to connect the contacts 11 and 12 whenever the arm 7 is on the contact 8 or 9.

45 13 and 14 are a pair of contacts arranged to automatically separate when permitted to do so; and 15 and 16 are a second pair of like contacts. The contact 13 is connected by the wire 17 to the contact 9; the contact 50 14 is connected to one terminal of the dim head-lamps 2 by the wire 18; the contact 15 is connected by the wire 19 to one terminal of the dash lamp 3 and the tail-lamp 4; and the contact 16 is connected by the 55 wire 20 to the contact 11. The generator 21 has one terminal connected by the wire

22 to the switch 5 and contact 12. The remaining terminals of the generator and the lamps are grounded to the frame of the car which is indicated by the bar 23.

24 and 25 are contacts connected respectively to the wires 17 and 19; and 26 and 27 are two switches connected by the insulating piece 28 and connected respectively to the wires 18 and 20. The switch members 26 and 27 are arranged to simultaneously engage the contacts 24 and 25, but the contacts are normally open, as they are for use only when the controlling mechanism is out of order.

The switch contacts or members 14 and 16 are forced against the contacts or members 13 and 15 by three cams 29, 30, and 31 on the face of the wheel or disk 32 having in its periphery or edge the six radial 75 slots 33 arranged 60 degrees apart, the cams being arranged 120 degrees apart and between consecutive slots. The wheel 32 is given step by step movements of 60 degrees by the pin 34 on the face of the disk 35, 80 having its shaft 36 parallel with the shaft 37 of the wheel 32.

38 is a lever pivoted at one end in the ears 39 and having its free end overlapping the disk 35 and adapted to ride on the ledge 40 on the disk 35 at the rear of the pin 34, the lever being forced toward the disk 35 by the spring 41 as soon as the ledge travels past the lever. The lever 38 has the lug 42 which interlocks with the wheel 43 of the usual alarm-train 44 of a clock mechanism, this train being driven by the usual spring in the spring-barrel 45. The post 46 of the spring-barrel carries the gear 47 which meshes with the pinion 48 on the shaft 36, 90 the latter having a gear 49 which meshes with the pinion 50 on the shaft 51 which carries the wheel 43.

52 is the time-controlling train of a clock mechanism, the escapement mechanism being omitted. 53 is the usual alarm-trip wheel which keeps in step with the hour-hand wheel 54, the driving-spring drum being shown at 55. The wheel 53 is loose on the trip or setting-shaft 56, and carries the hub or collar 57 having the notch 58 in its free edge, the notch having the inclined wall 59 leading to the said free edge. The wheel 53 has secured thereto the finger 60 which lies on the said free end of the collar 57, the latter being kept in contact with the finger by the spring-actuated arm 61

which is urged against the rear side of the wheel 53 by the spring 62. The shaft 56 is turned by means of the knob 63. The shaft 56 carries the pointer 64 which over-
5 lies certain numerals arranged as they are on a common clock-face. All the time-controlling mechanism 52 so far described is old and well known.

The spring-actuated arm 61 surrounds the
10 shaft 56 and extends to a point opposite the disk 35, where it is provided with the bell-crank lever having the arms 65 and 66 urged clockwise on its pivot 67 by the spring 68, the arm 61 having the stop-lug 69 to limit
15 the movement of the lever-arm 65 to a position overlying the disk 35. The lever-arm 66 is adapted to lie beneath the hook 70 on the arm 38 so as to lift the arm 38 when the notch 58 comes beneath the finger 60. The
20 lifting of the arm 38 lifts the stop-lug 42 away from the wheel 43 and allows the train of wheels driven by the wheel 47 to turn the disk 35.

When the automobile is driven after dark
25 and bright lights are desired, the switch 5 is set with the arm 7 on the contact 8, current passing from the generator 21 through the arm 7, the contact 8, the bright head-lamps 1 and the frame 23 to the generator 21. Also
30 current from the generator passes through the arm 10, the contacts 12 and 11, the wire 20, the contacts 15 and 16, the wire 19, the tail and dash lamps 4 and 3, and the frame 23 to the generator. The clock mechanism
35 will have previously closed the contacts 15 and 16 at a time predetermined by the setting of the shaft 56, exactly as the operation of an alarm would be tripped by the said shaft in the usual alarm clock.

40 If dim lights are desired, the switch 5 is moved so that the arm 7 engages the contact 9. Current from the generator 21 then passes through the wire 22, the arm 7, the contact 9, the wire 17, the contacts 13 and 14, the wire 18, the dim head-lights 2, and the frame 23 to the generator. The circuits of the dash and tail lamps remain as before.

45 In case the driver wishes to park his automobile before the legal time for lighting the lamps and to have the dim and tail lamps lit at a definite time, he places the switch 5 with the arm 7 on the dimmer contact 9 and sets the shaft 56 so that the notch 58 will come under the finger 60 at the said definite time. When that time arrives (the contacts 14 and 16 being previously off from any of the cams 29, 30, and 31, causing the contacts 13-14, and 15-16 to be open), the spring 62 forces the arm 61 out, causing the arm 66

55 to lift the arm 38 which lifts the trip-lug 42 from the stop-wheel 43. The gear-train driven by wheel 47 causes the disk 35 to rotate, the pin 34 turning the wheel 32 one-sixth of a revolution and bringing the next cam 29, 30, or 31, as the case may be, under

the contacts 14 and 16 and causing them to engage the contacts 13 and 15. Later the pin 34 engages the arm 65 and moves the bell-crank on its pivot 67 so as to withdraw the arm 66 from beneath the hook 70, whereupon the arm 38 is moved by the spring 41 to cause the lug 42 to engage the wheel 43 and stop the train of gearing. This operation leaves the arm 61 pressed outwardly. In order that the arm 38 may not drop until the pin 34 has passed beyond the arm 65, the ledge 40 is provided for the end of the lifted arm 38 to ride upon. The length of the ledge is such as to allow the arm 38 to drop soon after the pin has passed the arm 65. As the time-train travels, the notch 60 riding under the finger pushes the wheel 53 and the arm 61 inwardly until the outer end of the incline 59 is reached by the finger. At or slightly before this, the arm 61 has been moved inwardly enough to cause the arm 66 to ride down the inclined outer end of the hook 70, the bell-crank turning to permit the arm 66 to do this, and to snap back under the hook. It is thus seen that at a predetermined time the dim and tail and dash lamps will be lit and that they will remain lit unless interfered with, until the wheel 53 makes another revolution, at which time, say 12 hours later, the wheel 53 permits the arm 61 to be again raised. This again sets in operation the mechanism to rotate the wheel 32 one-sixth of a revolution and to move the cam from beneath the contacts 14 and 16, thereby opening the light-circuits, which will be again closed in twelve hours, if the mechanism is allowed to operate as described.

60 It is seen that when the switches 26 and 27 are closed, the lamps can be controlled by the switch 5, even though the clock mechanism is out of order so that the contacts 13-14, and 15-16 remain open.

65 Referring now to Fig. 4, I have omitted the dimming lamps, and provided for dimming the lamps 1 by the insertion of the resistance 71 in series with said lamps when the arm 7 is on the contact 9 and either the contacts 13 and 14 are closed or the switch 26 is on the contact 24. In this figure as well as in Fig. 1 all the lamp circuits may be opened by moving the switch 5 free from the contacts 8, 9, 11 and 12.

70 I claim—

75 1. In an electric light-controlling system, a time-clock having a tripping mechanism automatically releasable thereby at predetermined times, an electric circuit containing an electric lamp and a switch, an electric generator for the circuit, a motor-driven switch-controlling train of gears, means controlled by the tripping mechanism for releasing and stopping the said train of gears, a wheel driven step by step by the train of successive releases of the said tripping mech- 130

- anism, means carried by the wheel for closing and opening the switch at alternate steps, a manually controlled switch having alternate contacts, one of the contacts being 5 in series with the first switch, a second circuit including the generator, and a second lamp connectible to the second circuit by the second switch when on the remaining contact thereof.
- 10 2. In an electric light-controlling system, a time-clock having a tripping mechanism automatically releasable thereby at predetermined times, an electric circuit containing an electric lamp and a switch, an electric 15 generator for the circuit, a motor-driven switch-controlling train of gears, means controlled by the tripping mechanism for releasing and stopping the said train of gears, a wheel driven step by step by the train at 20 successive releases of the said tripping mechanism, means carried by the wheel for closing and opening the switch at alternate steps, a manually controlled switch having alternate contacts, one of the contacts being 25 in series with the first switch, a second circuit including the generator, a second lamp connectible to the second circuit by the second switch when on the remaining contact thereof, a third lamp, and contacts for the 30 third lamp closed by the second switch when the same is on either of its contacts.
3. In an electric light-controlling system, a time-clock, a pair of switches controlled thereby, dim-light and tail-light circuits 35 controlled by the respective switches, a bright-light circuit, and a manually-controlled switch having one contact in series with the dim-light circuit and another contact in series with the bright-light circuit.
- 40 4. In an electric light-controlling system, a time-clock, a pair of switches controlled thereby, dim-light and tail-light circuits controlled by the respective switches, a bright-light circuit, and a manually-controlled switch having one contact in series with the dim-light circuit and another contact 45 in series with the bright-light circuit, and to be disconnected when the latter switch is in open position.
5. In an electric light-controlling system, a time-clock, a pair of switches controlled thereby, dim-light and tail-light circuits controlled by the respective switches, a bright-light circuit, a manually-controlled switch having one contact in series with the dim-light circuit and another contact in series with the bright-light circuit and having contacts adapted to be placed in series with the tail-light circuit, and to be disconnected when the latter switch is in open position, and a second manually-controlled switch in shunt with the pair of switches.
6. In an electric light-controlling system, a light circuit, a time-clock mechanism, a motor driven mechanism, means controlled by the latter for opening and closing the light circuit, a lever having a stop device for stopping and releasing the motor-driven mechanism, and a lever controlled by the time-clock mechanism for operating the first lever.
7. In an electric light-controlling system, a light circuit, a switch therefor, a step-by-step wheel for controlling the switch, a wheel for operating the first wheel, a lever carrying a stop for releasing and stopping the second wheel, a time-clock mechanism, a lever operated thereby in two directions, a bell-crank carried by the lever and having one arm connected to the first lever to operate the stop to release the second wheel, and having a second arm operated by the second wheel to release the first arm from the first lever, and means whereby the second lever and the bell-crank may be automatically re-connected.

In testimony whereof, I hereunto affix my signature this 1st day of May, 1923.

FRED WALDORF.
